UNITED STATES PATENT OFFICE.

WARREN M. SMITH, OF BOROUGH OF PROSPECT PARK, PENNSYLVANIA,
ASSIGNOR TO JOHN A. BRILL, OF PHILADELPHIA, PENNSYLVANIA.

SEMICONVERTIBLE CAR.

SPECIFICATION forming part of Letters Patent No. 739,794, dated September 22, 1903.

Application filed May 13, 1903. Serial No. 156,928. (No model.)

To all whom it may concern:

Be it known that I, WARREN M. SMITH, a citizen of the United States, and a resident of the borough of Prospect Park, county of Delaware, and State of Pennsylvania, have invented new and useful Improvements in Semi-convertible Cars, of which the following is a specification.

This invention relates to railway-cars of an improved construction whereby either one or both of the upper and lower sashes of each window of the car may be lowered completely below the window-sill and with the lower end of the lower sash considerably below the upper portion of the side sill of the car, thereby enabling the car to be particularly well adapted for use as a closed or winter car or as an open or summer car.

The object of this invention is to provide an improved construction of the framework whereby the windows may be made of maximum length and when the car is in its open condition the sashes will be completely concealed in the sides of the car and also to provide a car which will be cheap, durable, and strong.

One embodiment of my invention which attains this object is disclosed in the following and in the annexed drawings, forming a part hereof, in which—

Figure 1 is a sectional view of a portion of my improved car, showing the sashes in the position which they occupy when the car is closed. Fig. 2 is a similar view showing the sashes in the position which they occupy when the car is open; and Fig. 3 is a sectional view taken on the line *a b* of Fig. 2, showing a portion of the car-framing. Fig. 4 shows a section of a sill and a stanchion and means for securing them together.

Throughout the various views similar reference characters designate similar parts.

The car-frame 1 is provided with side sills 2, which consist of an angle-iron 3, the vertical web 4 of which is secured to a wooden filling 5, and the horizontal web 6 is placed at the lower edge of the sill. A reinforcing iron 7 is secured to the filling 5 on its oppo-

site surface from the angle-iron 3, and the angle-iron filling and metallic strip are secured together to form the side sill of a car.

While I have shown and described only one side sill and the parts connected with it, it is obvious that the other side sill of the car is a duplicate and is similar in all respects.

Stanchions 8 extend from the roof of the car to the side sill 2 and are bolted to the angle-iron 3 and filling 5, as shown in Fig. 4, by means of bolts 8^a.

The stanchions 8 are provided with the usual grooves 8^b, 8^c, and 8^d for the sashes 9 and 10 and are connected on their inner edges by the side boards 11 and footboards, as is usual in such constructions.

On their exterior edges the stanchions 8 are connected by window-sills 13, which are provided with grooves 14 on their lower edges, to which the outer skin 15 of the car is secured. The lower edge of the outer skin 15 is secured to a wooden lining 16, which is fixed to the horizontal web 6 of the angle-iron 3. A rubber or other cushion 17 is placed on the lining 16 to prevent the sash 9 from being jarred.

The sill 13 and board 11 are connected by the hinged sill-pieces 18, which extend between the stanchions and may be raised when the sashes are to be moved into or out of the position they occupy when the car is open. The sill 2 is joined to the corresponding sill by means of crossings 19, which are secured to said side sills in any suitable manner, as by chairs 19^a and a flooring 20 on said crossings.

From the above it is obvious that my improved construction enables window-pockets to be formed in the side sills of a car, which extend outside of the side sills and below the upper portion of the side sills and below the upper portion thereof, thus enabling the windows to be made with the maximum length and without increasing the cost of manufacture of the car.

It is obvious that various changes may be made in the structure hereinbefore described without departing from the spirit and scope

of my invention and that my invention is not limited to this disclosure, but is defined in the following claims:

What I claim is—

1. In a car or similar vehicle, a sill comprising angle-iron with a horizontal web extending outwardly from the lower portion thereof, and a wooden filling secured to said angle-iron on the opposite side from said web.
2. In a car or similar vehicle, a sill comprising an angle-iron with a horizontal web extending outwardly from said lower edge, and a wooden filling on the inner side of said angle-iron and an iron reinforce secured to said wooden filling.
3. In a car or similar vehicle, side sills comprising an angle-iron with a horizontal web extending outwardly from the lower edge thereof, a wooden filling fixed to the inner surface of said angle-iron, and a strip fixed to the upper surface of said horizontal web.
4. In a car or similar vehicle, a sill comprising an angle-iron with an outwardly-extending horizontal web at its lower edge, a

wooden filling secured to the inner surface 25 of said angle-iron, and a strip with elastic cushions secured to the upper surface of said horizontal web.

5. In a car or similar vehicle, a sill comprising an angle-iron with an outwardly-extending horizontal web at its lower edge, and a wooden filling secured to its inner surface, and grooved stanchions secured to said angle-iron.

6. In a car or similar vehicle, a sill comprising an angle-iron with an outwardly-extending horizontal web at its lower edge, and a wooden strip secured to its inner surface, stanchions secured to said sill, window-sills uniting said stanchions, and a skin uniting 40 said window-sills and sills.

Signed in the city and county of Philadelphia, State of Pennsylvania, this 11th day of May, 1903.

WARREN M. SMITH.
